ICE-CREAM CABINET ATTACHMENT

Maximilian E. Weiss, Philadelphia, Pa.

Application July 15, 1950, Serial No. 173,996

2 Claims. (Cl. 220—15)

1

My invention is an attachment for preventing the turning and twisting of an ice-cream carton in a refrigerating cabinet while ice-cream is being scooped therefrom, and in its preferred form it comprises one or more grips for engaging the rim of a carton and a rim for supporting the grips and which is expansible and contractible to facilitate the insertion or the removal of the rim from the cabinet and provide a secure engagement between the rim and the cabinet.

Ice-cream is commonly vended to dealers in cylindrical paper-board cartons having reinforced edges, such as a flexible metallic rim, and is commonly stored in and vended from refrigerating cabinets having substantially rectangular compartments or wells which may be partitioned or non-partitioned. When ice-cream is scooped from the carton, the carton tends to turn and twist on its axis, and cannot be manually held against rotation without discomfort and likelihood of contamination of the ice-cream. If it is sought to clamp the carton to a base with sufficient force to prevent rotation, the paper-board walls tend to bulge or collapse under the stress as the carton is emptied.

A leading object of my invention is to prevent the rotation of a carton without applying sufficient force lengthwise thereof to buckle its walls. A further object of my invention is to provide an attachment for preventing the rotation of a carton without itself becoming irremovably frosted to the cabinet or to the carton. A further object of my invention is to provide an attachment which is readily insertable into and removable from the cabinet and adaptable for securing cartons of different heights against rotation.

In the preferred embodiment of my invention, a carton is held against rotation by the engagement of its reinforced rim in narrow rectangular slots formed by jaws of grips comprising leaves hingedly connected with a contractible and expansible rim which may be readily inserted in the well of a cabinet and expanded against the walls thereof in position to encircle one or more cartons in the well. The grips are preferably located on indented sections of the rim spaced from the cabinet wall so as to minimize the transmission of heat and the accumulation of frost around the grip and the rim is contractible and expansible by rack and pinion mechanism so that the rim can be firmly secured against the cabinet wall or released therefrom despite any frosting between the rim and wall.

The principles of my invention and the best mode in which I have contemplated applying such

2

principles will further appear from the following description and the accompanying drawings in illustration thereof.

In the drawings, Fig. 1 is a top perspective view of an ice-cream cabinet having the covers broken away to display attachments embodying my invention and cartons secured thereby; Fig. 2 is a top plan view of the right-hand portion of the cabinet shown in Fig. 1; Fig. 3 is a fragmentary sectional view taken on the line 3—3 of Fig. 2 to show the rack and pinion mechanism for expanding and contracting the rim of my attachment; Fig. 4 is a fragmentary sectional view through the rim of my attachment taken on the line 4—4 of Fig. 2; Fig. 5 is a transverse sectional view taken on the line 5—5 of Fig. 2; Fig. 6 is an enlarged fragmentary view showing one of the grips of my attachment engaging a carton rim; Fig. 7 is an irregular fragmentary sectional view taken on the line 7—7 of Fig. 6; Fig. 8 is an irregular sectional view showing a catch of my attachment rocked upward out of engagement with a carton with which it is connected in Fig. 7; Fig. 9 is a fragmentary elevation of a grip of my attachment taken on the line 9—9 of Fig. 6 with the carton removed; Fig. 10 is a transverse sectional view taken on the line 10—10 of Fig. 2 and Fig. 11 is a fragmentary sectional view taken on the line 11—11 of Fig. 2.

30 In the drawings there is shown a conventional ice-cream cabinet 1 containing rectangular refrigerating compartments or wells 2 surrounded by walls 3, and which may but need not be separated from one another by partitions 4 extending downwardly to the bottom of the cabinet.

The wells 2 are ordinarily filled with cylindrical ice-cream cartons 5 whose height sometimes approximates the depth of the well, but more frequently shorter cartons are stacked on top of one another as indicated in Fig. 1. These cylindrical cartons are ordinarily made of paper-board reinforced by flexible metallic rims 5' bent over the upper edges of the cylindrical walls of the cartons. The cartons are ordinarily filled with frozen comestibles, such as ice-cream, to within a short distance of the top of the carton. The ice-cream is vended from the carton by digging into it with a scoop, which tends to turn and twist the carton and displace it from its position in the well.

50 In accordance with my invention, this turning, twisting and displacement of the cartons is prevented by securing one or more grips 6 to the rim of each container, and preferably at opposite sides thereof. Preferably each grip com-

prises a pair of leaves 7 and 7' hinged together by a pintle 7". The leaf 7 has its edge opposite the pintle 7" turned downward to form a flange having a central portion 8 slit and bent outward to provide a lift and leaving fingers 9 on opposite sides thereof. Fingers 10 are cut and bent downward from the leaf 7 in spaced substantially parallel relation to the fingers 9 to form therewith a narrow slot for the reception of the rim 5' of a carton. Preferably, the effective length of the slot should subtend approximately 10° of arc of the rim 5' and the slot should be so narrow between the fingers 9 and 10 as to require a slight deformation of the arc of the rim 5' to effect its insertion in the slot. Such proportioning of the slot effectively prevents the sliding of the carton rim 5' therethrough. The leaf 7 may be locked in horizontal position by a substantially L-shaped latch 11 pivotally connected with the leaf 7' by one of the bolts 12 by which each leaf 7' is secured to an indented portion 13 of U-shaped rim sections 14 and 15. The section 14 has bolts 16 fixed in the opposite legs thereof and a wing nut 17 is sleeved on and a wing nut 18 is threaded on each bolt 16. The wing nut 17 has a hub 19 provided with peripheral teeth 20 forming a pinion engaging teeth 21 on the upper side of a slot 22 in each leg of the rim section 15. Headed studs 23 have shanks 24 passing through slots 25 in opposite legs of the section 15 and fixed in the opposite legs of the section 14 to permit the rectilinear expansion and contraction of the rim formed by the sections 14 and 15 but prevent the turning of such sections about the axes of the bolts 16.

The cross bars of the sections 14 and 15 are provided with knurled surfaces 26 for frictionally gripping the end walls of the wells 4, and the curved corners 27 adjacent to the ends of the knurled surfaces 26 are grooved to form reinforcing ribs 28 to add rigidity to the structure.

In utilizing my improved device, it is ordinarily preferable to first deposit the filled cartons in the well of the cabinet and to then insert my improved retaining device, above described, after rotating the wing nuts 17 to constrict the overall length of the rim sufficiently to permit it to be lowered in the well until its top is approximately level with the upper edges of the cartons to be restrained. The wing nuts 17 are turned to expand the rim sections 14 and 15 so as to engage the knurled surfaces 26 firmly against the end walls of the well 4, and the wing nuts 18 are then tightened to secure the members 14 and 15 in expanded position. Each leaf 7 is then turned to a horizontal position so that its fingers 9 and 10 grip the inner and outer surfaces of the rim of the carton. Each leaf may be then secured against disengagement with the carton by turning the latch 11 into locking position. The spacing of the sections 13 and 27 from the wall of the well and the engagement of the grips 6 with the carton above the ice-cream level minimizes any tendency to frosting, and such slight frosting as may take place may be readily broken by ap-

plying upward pressure to the lifts 8 and partially unscrewing the wing nuts 18 and turning the wing nuts 17 to transmit torque through the pinion teeth 20 to the rack teeth 21 and thereby contract the rim sections 14 and 15. The cartons are securely held by my improved device against turning or displacement without the imposition of stresses tending to bulge or distort the paper walls, and when the upper cartons have been emptied they may be removed by merely unlatching the latches 11 and turning the leaves 7 upward. If the exhausted cartons are replaced with cartons of the same height the leaves 7 may be rocked into locking position and latched by the latches 11 without any detachment of the rim sections 14 and 15, or if cartons of different height are inserted, or the lower layer of cartons are to be used, the rim sections 14 and 15 may be contracted and lowered to appropriate position and then expanded and secured at a level permitting the fingers 9 and 10 to grip the walls of such cartons.

Having described my invention, I claim:

1. An attachment for preventing the rotation of a carton in a cabinet and comprising a rim consisting of a complementary pair of substantially U-shaped sections, one of said sections containing slots each having a toothed edge, pinions pivotally connected with the other of said sections and each meshing with a toothed edge, clamps for securing the respective pinions relatively to its respective complementary edge, said sections each having indented portions, and grips connected with said indented portions and having jaws hinged to said indented portions for engaging the rims of cartons encircled by said rim first named.

2. The combination with a cabinet having walls forming a well for a carton and a carton in said well, of an expandible rim expanded against said walls, said rim having indented sections spaced from said walls, grips mounted on said indented sections each of said grips comprising a leaf hingedly connected with an indented portion of said rim and overlying the wall of said carton within said well, said leaf having a flanged edge engaging in the inner wall of said carton and fingers bent downwardly and engaging the outer wall of said carton, said flanged edge having a lip bent therefrom away from the inner wall of said carton.
